UNITED STATES PATENT OFFICE.

WILLIAM O. VIVARTTAS, OF WEEHAWKEN, NEW JERSEY.

DUST-CAP FOR PNEUMATIC TIRES.

1,385,055.

Specification of Letters Patent. Patented July 19, 1921.

Application filed March 25, 1920. Serial No. 368,492.

To all whom it may concern:

Be it known that I, WILLIAM O. VIVARTTAS, a citizen of the United States, and a resident of Weehawken, in the county of 5 Hudson and State of New Jersey, have invented certain new and useful Improvements in Dust-Caps for Pneumatic Tires, of which the following is a full, clear, and exact description.

10 Among the principal objects which the present invention has in view are: to diminish the time usually required for installing in service the dust caps associated with the valve stems of pneumatic tires; to prevent the accidental displacement of said 15 dust caps; and to simplify and cheapen the construction of the improved dust cap.

Drawings.

20 Figure 1 is a longitudinal section of a dust cap constructed and arranged in accordance with the present invention, showing in conjunction therewith a valve stem of the character mentioned, the section 25 being taken as on the line 1—1 in Fig. 2;

Fig. 2 is a cross section of the cap and stem, the section being taken as on the line 2—2 in Fig. 1.

Description.

30 Heretofore dust caps which have been employed for the protection of valve stems, and for the parts of the tire associated therewith, have been furnished with a 35 screw-threaded section of a pitch corresponding to the screw-threaded sections 9 on the valve stem, and at either side of the flat faces 10 provided on the said stems, to secure the proper alinement thereof in 40 service. The time required to screw the dust cap down over the relatively long stem has been considerable, with the result that it has added a great deal to the time necessary for the inflation of tires of the character mentioned. This difficulty has been 45 one that the automobilist has found irksome, with the result that in many instances the dust caps have been omitted, either intentionally or unintentionally, after the 50 tires have been inflated.

To avoid this the present dust cap slides over the stem and does not engage directly the threaded sections 9. The threads of these sections 9 are, however, utilized as 55 engaging points for a rubber packing or

jack 11, which is disposed within the housing section 12 on the dust cap. The section 12 is increased in diameter over the section 13, and provides at the junction therewith, a shoulder 14 to form an abutment against which the jack 11 is pressed or crowded. The jack is compressed by a ram 15, which is externally threaded to engage an internal thread provided within the housing section 12. As seen best in Fig. 65 2 of the drawings, the ram 15 has an elongated opening 16, shaped in correspondence with the valve stem having parallel sides for a sliding fit on the flat sides 10 of the valve stem. The ends of the opening 16 are extended to avoid the threaded sections 9 of the valve stem.

From the foregoing it is obvious that when the rubber jack 11 is not compressed, the dust cap may be moved lengthwise of 75 the valve stem at will, there being none other than a free sliding engagement between the dust cap and the valve stem. When, however, the dust cap is rotated about the ram 15, the ram is caused to 80 travel within the housing section 12 toward the shoulder 14 by reason of the screw-thread engagement existing between said housing and the said ram.

The rubber gasket or jack 11 is thereby 85 compressed lengthwise, the material thickening or expanding laterally in compensation therefor. The inner wall of the jack 11 crowds upon and fits into the threads of the sections 9, thereby anchoring the 90 dust cap to prevent the lengthwise movement thereof in the valve stem. A half turn of the dust cap is usually sufficient to compress the jack 11 sufficiently to force the same into engagement with the stem. 95 If closer engagement is desired, this is obtained by continuing the rotation of the dust cap.

To avoid adhesion of the gasket or jack 11 to the ram 15, with the consequent tendency to drag or twist the said gasket or jack, there is provided a thin metal washer 17, which operates as a shoe or protective facing for the said jack.

When it is desired to remove the dust 105 cap the said cap is reversely rotated to cause the ram 15 to travel toward the retaining flange 18 with which the housing 12 is provided. The flange 18 is spun over the chamber formed by the housing 12. 110

after the ram 15 has been introduced. Thereafter the said ram is prevented from passing out of the said housing.

Claims.

5. 1. A dust cap for service with a pneumatic valve embodying a mutilated cylindrical stem, said cap comprising a tubular body closed at one end for enfolding freely said stem; an open-centered ram held permanently in said body, the opening in said ram being shaped in correspondence with said stem for holding said ram on said stem non-rotatively to move freely lengthwise thereover; an open-centered yielding packing member supported within said body for distention to engage said stem; and means operatively connecting said body

and said ram for moving said body toward said ram for distending said member when 20 said body is rotated.

2. A dust cap for service with a pneumatic valve embodying a threaded mutilated cylindrical stem, said cap comprising a tubular body closed at one end for enfolding freely said stem; an open centered ram 25 permanently mounted in said body and having screw-thread engagement therewith, said ram being adapted to move freely lengthwise of said stem and to be held non-rotatively thereby; a soft bodied packing member interposed between said ram and said cap to be compressed thereby and means for preventing an edge of said packing member from engaging said stem. 30 35
